UNITED STATES PATENT OFFICE.

HANS P. HUSBY, OF CHICAGO, ILLINOIS, ASSIGNOR TO THE GOSS PRINTING PRESS COMPANY, OF CHICAGO, ILLINOIS, A CORPORATION OF ILLINOIS.

FOLDING APPARATUS FOR PRINTING-PRESSES.

No. 884,587.

Specification of Letters Patent.

Patented April 14, 1908.

Application filed March 29, 1907. Serial No. 365,803.

To all whom it may concern:

Be it known that I, HANS P. HUSBY, a citizen of the United States, residing at Chicago, in the county of Cook and State of Illinois, 5 have invented certain new and useful Improvements in Folding Apparatus for Printing-PresSES, of which the following is a specification, reference being had to the accompanying drawings.

10 My invention relates to printing presses, and has particularly for its object to provide new and improved apparatus for transversely folding sheets received from a perfecting press.

15 It consists in the construction and arrangement illustrated in the drawings and herein-after described.

What I regard as new is set forth in the claims.

20 In the accompanying drawings,—Figure 1 is an end elevation of a folding cylinder and adjacent parts, being a section taken on line 1—1 of Fig. 8; Fig. 2 is a sectional view on line 2—2 of Fig. 3; Fig. 3 is an end elevation 25 of one of the cross-heads by which the folding blades are operated; Fig. 4 is an edge view thereof; Figs. 5, 6 and 7 are perspective views of certain of the cams which control the operation of the folding blades; Fig. 8 is a view 30 taken at an angle of ninety degrees to the view shown in Fig. 1; Fig. 9 is a perspective view of one section of the folding blade.

Referring to the drawings,—10 indicates the folding cylinder, which is mounted on a 35 shaft 11 in the usual way,—said shaft being supported in the side members 12—13 of the frame of the press, as shown in Fig. 8.

14—15 indicate folding rollers arranged in juxtaposition adjacent to the cylinder 10 in 40 the usual way. Said rollers are mounted on shafts 16—17, as shown in Fig. 1, and serve to fold the sheets delivered to them by the folding-blades on the cylinder 10.

18—19 indicate shafts carried by the cylinder 45 10 near the periphery thereof and set 180 degrees apart. The shaft 18 carries a folding-blade 20, and the shaft 19 a folding-blade 21, which, as shown in Figs. 8 and 9, are best composed of a number of sections 22, but the 50 specific construction of the folding-blades has nothing to do with my present invention, and any suitable type of blades may be employed.

23—24 indicate cams secured to the side-member 12 of the frame of the press, as

shown in Figs. 1 and 8. The cams 23—24 55 are arranged adjacent to the folding rollers 14—15 and coöperate to properly guide the folding-blades so that they fold the sheets intermediately and tuck them into the bite of the folding rollers 14—15.

25 indicates a cam arranged below and somewhat at one side of the cams 23—24,—said cam being also secured to the side-member 12 of the frame of the press by means of an intermediate block 26, shown in Fig. 8. 60

27 indicates cross-heads, one of which is mounted upon the end of each of the shafts 18—19 which is adjacent to the cams 23—24, and is non-rotatably secured thereto. Each 70 of said cross-heads 27 is provided with a central hub 28 by which a firmer connection is provided with the shaft upon which it is mounted, and at its ends is provided with two pairs of rollers 29—30 and 31—32, re-

spectively, the rollers 29—30 being at one 75 side of said cross-head, and the rollers 31—32 at the other side. Furthermore, the rollers 31—32 are arranged so that a plane intersecting their axes is coincident with the plane of the folding-blades, while a plane intersecting the axes of the rollers 29—30 intersects the plane of the folding-blades at an acute angle.

It is to be understood that while I prefer to support the rollers 29—30 and 31—32 by a single integral cross-head, 80 as described, my invention is not restricted to this particular construction, as they may be supported in any other suitable way, provided they are arranged as described,—to wit in intersecting planes. The parts carried by the cross-head 27 are similar to those described, and consequently need not 85 be referred to specifically.

33 indicates a ring-shaped cam, the ends of which are connected to the end portions 95 of the cam 25, as shown at 34 and 35 in Fig. 1. Said cam is also secured to the side-

member 12 of the frame of the press, as shown at 36 in Fig. 8. The rollers 29—30 and 31—32 are secured to the cross-head 27 100 by pivots 37, as shown in Fig. 2, or in any other suitable way.

The operation is as follows:—Assuming that the folding cylinder 10 rotates in the direction of the hands of a clock, as indicated by the arrow in Fig. 1, when the parts are in the position shown in Fig. 1, the roller 30 will engage the cam 24, and the roller 29

2
will ride on the inner edge of the cam 23. As it still continues to rotate, the cross-head 27 will be rocked to move the leading edge of the folding-blade down between the 5 folding rollers 14—15, at the same time moving the roller 32 into the recess 38 in the upper side of the cam 25, as shown in Fig. 7. When the parts reach the position shown in dotted lines in Fig. 1, the folding blade will 10 be in an upright position, its lower edge being down at its lowest point, between the rollers 14—15. At this time the roller 29 will be about to pass over the apex of the cam 24. Further rotation of the cylinder 15 will cause said roller to ride on the inner margin of the cam 24,—the roller 32 then running on the inner margin of the cam ring 33, the folding blade being thereby withdrawn from between the rollers 14—15. 20 The parts will afterwards assume the position shown at the top in Fig. 1 being held in such position by the cam ring 33 until the cam 23 is again reached.

By providing the folding-blade with guide 25 rollers arranged in a plane which intersects the plane of the folding-blade the cams which operate on said rollers or bowls do their work more smoothly and without any knock or blow, as they operate at a more 30 favorable angle, so that they obtain a sufficient leverage to turn the folding-blade into and out of operative position without any such knock or blow or labor on the stationary 35 folding cams. The guide rollers or bowls arranged in the plane of the folding-blade or knife operate to guide the folding-blade accurately into the folding cam, bringing the edge of the folding-blade into position and returning it from operative position on 40 the same curve, thereby making certain that the edge of the folding-blade will not touch the folding rollers or have any parallel motion at its lowest point by which it might strike the folding rollers.

45 By this construction I am able to dispense with movable cams,—the entire operation of folding being effected by means of stationary cams,—which is a decided advantage.

50 It will be understood that instead of using rollers on the cross-head any other equivalent devices may be employed and the term “rollers” as used in the claims is to be construed accordingly.

55 That which I claim as my invention, and desire to secure by Letters Patent, is,—

1. In a folding apparatus for printing presses, a folding cylinder, a folding-blade carried by said cylinder, folding rollers connected 60 acting therewith, guide rollers connected with the folding-blade and arranged in a plane which intersects the plane of said folding blade, and stationary cams adapted to en-

gage the latter rollers for actuating said folding-blade. 65

2. In a folding apparatus for printing presses, the combination of a cylinder, a folding-blade carried thereby, folding rollers co-operating therewith, a pair of guide rollers in the plane of said folding-blade, a pair of guide 70 rollers in a plane intersecting the plane of the folding-blade, and stationary cams adapted to be engaged by said rollers and operating to actuate said folding-blade.

3. In a folding apparatus for printing 75 presses, the combination of a folding cylinder, a shaft carried thereby, a folding-blade carried by said shaft, folding rollers co-operating with said folding-blade, a cross-head carried by said shaft, guide rollers carried by 80 said cross-head in a plane which intersects the plane of said folding-blade, and stationary cams adapted to be engaged by said guide rollers for actuating said folding-blade.

4. In a folding apparatus for printing 85 presses, the combination of a folding cylinder, a shaft carried thereby, a folding-blade carried by said shaft, folding rollers co-operating with said folding-blade, a cross-head carried by said shaft, a pair of guide rollers carried by 90 said cross-head in the plane of said folding-blade, a pair of guide rollers carried by said cross-head in a plane which intersects the plane of said folding-blade, and stationary 95 cams adapted to be engaged by said guide rollers for actuating said folding-blade.

5. In a folding-apparatus for printing presses, a rotary carrier, a folding-blade carried thereby, folding rollers coacting therewith, guide rollers connected with the folding-blade and arranged in a plane which intersects the plane of said folding-blade, and stationary means adapted to engage said guide 100 rollers for actuating the folding-blade.

6. In a folding-apparatus for printing 105 presses, a rotary carrier, a folding-blade carried thereby, folding rollers coacting therewith, guide rollers in the plane of the folding-blade and connected therewith, guide rollers connected with the folding-blade and arranged in a plane which intersects the plane 110 of said folding-blade, and means adapted to engage the latter guide rollers for actuating the folding-blade.

7. In a folding apparatus for printing 115 presses, a folding cylinder, a folding blade carried by said cylinder, folding rollers coacting therewith, two pairs of guide rollers arranged in intersecting planes, and means co-operating with said rollers for actuating the 120 folding blade.

HANS P. HUSBY.
